TRAFFIC DETECTION APPARATUS

John L. Barker, Norwalk, Conn., assignor, by
mesne assignments, to Eastern Industries, In-
corporated, a corporation of Delaware

Application June 29, 1944, Serial No. 542,729

18 Claims. (Cl. 177—337)

1
This invention relates to improvements in ultra high frequency signalling apparatus, and particularly to an improved means for using ultra high frequency electro-magnetic or radio waves for periodically examining traffic conditions along one or more rights of way to detect the presence of vehicles thereon.

The invention is particularly useful in the control of vehicular traffic at intersections of two or more roadways according to the traffic conditions prevailing thereon, although it will be apparent from the ensuing description that the invention is capable of many other applications.

Automatic traffic control systems may be classified into two broad groups: fixed-time sequence systems and traffic-actuated systems. The ordinary "stop and go" installations employing signals for street traffic control and regulated by a timing device which exhibits the signals in a fixed-time sequence irrespective of traffic conditions in the streets, are inefficient in that the stop signal is frequently displayed against streets having moving traffic, and right of way is given to an intersecting street on which there are no waiting vehicles. The second broad classification includes systems whereby the time cycle of right of way on a traffic lane is initiated or modified by electrical impulses created by the passage of moving traffic over a contactor or other roadway installation and conveyed by a cable installation or the like to a detecting apparatus wherein the traffic conditions are analyzed and right of way given as most appropriate to the particular condition.

The latter traffic control system has a fault in that the impulse generating stations are best located, to meet an average traffic condition, at locations relatively distant from the intersection, and may thus fail to provide for local conditions in which an alley or infrequently used driveway enters the street between the position of the actuator and the intersection.

A feature of the present invention resides in the employment of means whereby roadway-embedded signal actuators, or other contactors requiring permanent cable connection with the traffic detection system, are supplanted by ultra high frequency transmission and detection apparatus which detects vehicle activity over a relatively large zone in as many rights of way as the location requires.

Another feature of the present invention resides in its ability to periodically explore traffic conditions along one or more of several traffic

2
lanes in a time sequence which may be regulated as desired.

Accordingly, the present invention embodies means for periodically testing traffic conditions along one or more rights of way and utilizing the detected presence or movement of vehicles to institute such traffic control as is desirable for the existing traffic condition in the said right of way.

10 It is well-known that ultra high frequency or hyper frequency radio waves have quasi-optical characteristics in that such waves may be transmitted from a wave guide along a lane of relatively narrow width and will be reflected in substantial measure from metal or other surfaces of an object which comes within the path of the transmitted waves.

The high frequency waves, which are advantageously of a frequency capable of transmission by wave guides, may be suitably generated and projected, by means of a suitable antenna and wave guide, in a relatively narrow directional beam or pattern. The wave reflected from a vehicle in the lane may be intercepted by the same wave guide and antenna, or the transmission and reception means may be separated as desired. In either method of operation, the time spacing between the instant of transmission of a wave and the instant of reception of the reflected portion of the wave is compared to establish the distance of the reflecting surface from the transmitter, assuming negligible relative distance between transmitter and receiver.

Operational advantages result from the use of 35 a frequency modulated system embodying transmitting a frequency modulated ultra high frequency wave and beating the reflected wave against the transmitted wave, with a resultant beat frequency which is characteristic of the distance of the reflecting surface from the transmitter-receiver unit. The transmission and reception apparatus may be arranged for continuous or intermittent transmission, as desired, it being understood that the period of transmission along the traffic lane is of such duration as to afford adequate comparison of the transmitter and received-reflected wave for operation of devices responsive to the beat frequency. The output from the transmitter-receiver unit may be 40 amplified and utilized to operate a relay or like device in a frequency selective circuit to actuate apparatus responsive only to a beat frequency or beat frequency range corresponding to the desired vehicle detection distance in the traffic lane.

As previously mentioned, the invention contemplates the periodic testing of traffic conditions in one or more lanes, by the projection of ultra high frequency electromagnetic waves along said traffic lanes. Operation is simplified by the continuous generation of said ultra high frequency wave and a periodic gating of the wave guides, so that transmission—and reception of a reflected wave—may be accomplished, at a particular instant, only through selected wave guides, the remainder being non-transmitting during such instant.

For traffic detection purposes, in which the apparatus is exposed to the elements and must operate under adverse weather conditions and in remote locations, it is desirable to use means for creating an electrical reflecting surface within the wave guide or directional horn from which transmission of the ultra high frequency wave is to be prevented at a particular instant or period.

Accordingly, a preferred form of the present invention contemplates the employment of a two-electrode gaseous tube disposed within the wave guides or the directional horns thereof. By impressing a voltage across the electrodes of the tube, the gaseous content thereof is ionized, creating a highly effective reflecting surface across the wave guide. By suitable timing means the wave guide or horns thereof may be so gated that transmission and reception of the radio waves may be had at a particular instant only through preselected horns of the installation.

By correlating with the gate timing means, means for connecting the amplified resultant of the compared transmitted and reflected waves to an electrical apparatus allocated to the horn or horns which are transmitting, the plurality of streets or traffic paths may be periodically examined and the intelligence conveyed by the combined transmitted and received wave may be utilized as desired.

It is therefore an object of the invention to provide apparatus which by means of ultra-high frequency electro-magnetic waves may be used to detect the presence of vehicles in a plurality of traffic lanes.

It is a further object of the invention to provide improved means whereby an ultra-high frequency wave may be successively projected in different directions by means of a wave guide having appropriately directed horns and gate means which permit transmission from the respective horns of the wave guide according to a predetermined timed sequence.

It is still another object to utilize a common transmitting and reception unit having means for successively projecting an ultra high frequency or hyper frequency wave along predetermined traffic lanes and receiving a reflection of said wave from a vehicle or the like in the traffic lane along which the wave was projected.

It is another object of the invention to employ a wave guide or equivalent for beaming ultra-high frequency electromagnetic waves periodically and successively along specified traffic lanes, and to compare the transmitted wave with a wave reflected from a vehicle thereon to determine the distance of such vehicle from the transmitter station and to appropriately operate a relay or the like which is allocated to the traffic lane from which the reflected wave originated.

In the accompanying drawings, which show various embodiments of means for accomplishing the objectives of the invention:

Fig. 1 is a diagrammatic representation of in- 75

tersecting highways, at the center of which is disposed ultra high frequency transmitting and detecting equipment embodying the instant invention;

Fig. 2 is a representation of one form of multi-horn wave guide, the directional horns of which are individually equipped with gate means; the figure also shows schematically a mechanically actuated timing switch by means of which the respective gate means are successively operated and a relay device serving a particular directional horn is connected into the receiver circuit coincident with the periods of transmission of the said horn;

Fig. 3 is a plan section of a horn of the wave guide taken on lines 3—3 of Fig. 2;

Fig. 4 is a similar plan section taken on lines 4—4 of Fig. 2;

Fig. 5 is a schematic representation of a gated transmitter horn and a gated receiver horn arranged as individual units;

Fig. 6 is a representation of the periods of operation and non-operation of the respective gates of a four-horn installation during one complete operative cycle and corresponding operative periods of the output-actuated devices;

Fig. 7 is a circuit diagram of an electronic sequence or timing switch, as applied to a two-gate installation; and

Fig. 8 is a schematic representation of a multi-horn wave guide utilizing two gates for controlling transmission therefrom.

The following description is illustrative of an application of the invention to vehicular traffic control installations. It is to be understood that the two street intersection of Fig. 1 is not used in a limiting sense; the invention may be applied to traffic intersections of more complex character, and has application to many traffic control situations not involving intersecting highways.

Referring to the drawings, the intersecting highways schematically shown in Fig. 1 are designated "N," "E," "S," and "W" respectively. Disposed at a suitable elevated level at the intersection as by an arm 12 carried by a standard 14, is an oscillator-receiver unit 10 associated with which is a multi-directional wave guide 11. It will be understood that Fig. 1 is grossly out of scale, and the depicted angle of equipment with respect to the roadway is not representative of installation practice.

The wave guide 11 has directional horns HN, HS, HE, HW, so arranged that an ultra high frequency wave emanating therefrom will be projected along the approaching traffic lane of the respective highways. The height of the wave guide above the intersection and the relative angle of the horns thereof with respect to the roadway will largely determine the distance from the intersection, of a substantially clearly defined zone within which an approaching vehicle will come into the effective field of the high frequency wave projection.

It will be understood that this zone may be selected as demanded by local conditions. For example, where an alley or driveway enters a highway at a relatively short distance from the intersection, it would be most desirable to be able to detect the presence of vehicles entering the highway therefrom, and the ultra high frequency zone would be established to include the point of entry of such alley or driveway. Conversely, and particularly on parkway installations, there may be no points of entry to the highway for a considerable distance, and the average speed of ve-

hicular traffic may be greater. Accordingly, the zone of detection may be disposed at a relatively greater distance from the detector unit.

Referring now to Fig. 2 an oscillator-detector-amplifier unit 10 may comprise any suitable apparatus by means of which an ultra-high frequency or hyper-frequency oscillation within a range capable of transmission by wave guides may be transmitted and a reflected wave compared therewith. Unit 10 includes an antenna 16 disposed within a chamber 17 at the base of the wave guide 11. Said wave guide may comprise a vertically extending rectangular metallic tube 18, at the upper end of which are the directional horns HE, HW, suitably positioned beneath HS and HN. By suitably flaring the ends of the said horns, a narrow beam having desired directional properties may be projected along the approaching right of way of the respective highways. A flare angle of fifty (50) degrees, for example, is known to afford a good directional pattern for the transmitted waves.

The horns HN and HS which, in the installation shown, conduct the electromagnetic wave about an angle, may have appropriate configuration, as at 20 and 21, see Fig. 4.

In the four-horn embodiment of Fig. 1, each has a resonance chamber within which is disposed a gaseous tube which functions as gate means for the horn. Said tubes in the East and West horns are designated TE and TW; and it is understood that the North and South directed horns are provided with gate tubes, which may be identified as TN and TS respectively.

It is contemplated that traffic conditions will be periodically explored along the individual highways, or simultaneously along pairs of highways, such as NS, or EW. Taking as an example of operation, the testing of the presence of traffic in individual highways, Fig. 6 shows a cycle diagram in which is shown in double line, the periods during which the respective horns are non-transmitting, and in single line the portion of the period of transmission of a horn during which the relay or like device allocated to said transmitting horn is connected into the output circuit of the transmitter receiver.

For energizing selected gates according to the desired time schedule there may be employed a timing or sequence switch, of which 22, Fig. 2, is a schematic representation of a mechanical timer. A motor 23, of adjustable speed, or operating through adjustable speed transmission, is organized to rotate a shaft 24 at a desired rate of speed. The shaft 24 terminates in a cam 25, desirably of di-electric material, and operatively associated with switches individual to the respective gates. Said switches are designated SE, SS, SW, and SN respectively; and each may comprise a movable contact 26 biased toward the cam and functioning as a cam follower, and a fixed contact 27. Said switches may be in circuit with the respective gates as shown in Fig. 2 with the power source 28 and resistances 29 such as to provide sufficient ionization of the gate tubes for reflecting the electromagnetic waves.

The cam 25 is so configurated that over successive periods of approximately $\frac{1}{4}$ cycle the circuit to each of the gates will be open, the circuit to other of the gates being closed. Hence, assuming a continuously generated ultra high frequency electromagnetic wave, the said wave may be projected through only such of the horns as is

desired by closing the circuit to the gates of the other horns.

A complete cycle of operation of each of the horns may comprehend such time period as is desired. As an example, a periodic examination at the rate of one cycle per second should be sufficient for usual vehicle activity. During the interval when an open gate permits of operation of a horn, it transmits the ultra high frequency wave and receives the wave which may be reflected from a vehicle in the traffic lane served thereby.

In the circumstance of using a frequency-modulated transmission system, and the comparison of transmitted and reflected waves by beating the latter against the former to obtain a beat frequency characteristic of the distance of the reflecting vehicle, the antenna 16 is in circuit with receiver-amplifier means in housing 10, and the amplified signal, converted to audio-frequency range, may be conducted by output leads 30, 31, through timer 22 to actuate electrical devices individual to the respective horns.

Said output-responsive devices, for purposes of illustration, may be relays RE, RW, RN, RS, in circuit with apparatus (not shown) which utilizes the closing of a relay circuit to operate the traffic signal or control apparatus, counting apparatus, or warning signal devices, as desired.

The interconnection of a relay and its associated operating horn may be accomplished by a cam 33 rotated by the shaft 24 and cooperating with normally open switches RSE, RSW, RSN, and RSS comprising movable contacts and fixed contacts, arranged in any suitable manner.

The cam has a rise 33' comprehending an arc slightly less than $\frac{1}{4}$ cycle and effective to sequentially close the switches serving the respective relays. It is apparent that during the period when one relay switch is closed the gate switch of the corresponding horn is open, and when the horn gate switches of the remaining horns are closed, the relay switches corresponding to said horns are open. By connecting each output-responsive device into the output circuit of the transmitter-receiver a fraction of a cycle later than transmission commences from its respective horn, and disconnecting the device prior to the changeover of transmission from said horn to the next horn, transient conditions during the changeover instant are not transmitted to the output-responsive device, and possible "false" signals to said device are eliminated. In other words, operating conditions at a horn are stable during the period of connection of the relay or like responsive device.

It will be understood that during the fractions of a cycle represented in Fig. 6, the output devices may be in circuit continuously during such period or for such portion or portions thereof as desired.

Fig. 5 schematically illustrates an embodiment of the invention in which the transmitter-oscillator 100 is in a unit apart from the receiver-amplifier 200; each such unit has an individual wave guide T18 and R18, and an individual antenna, (not shown). The receiving wave guide R18 may be served by an antenna R16, connected by coaxial cable to the unit 200.

The transmitting and the receiving wave guide terminates in a directional horn TA and RA respectively, or, as shown in dotted line, additional horns, such as TB and RB. The respective horns are gated, as shown by GA, GB, GRA and GRB, operation of which is controlled by a sequence 75 switch 220 having cam-operated switches GSA

and GSB and GSRA and GSRB, respectively. When mechanically actuated switches are used, they may be as previously described with respect to Fig. 2.

The transmitted and reflected-received waves may be combined in the receiver-amplifier 200, and the amplified output from each pair of transmitting and receiving horns connected through synchronized cam switch RSA or RSB to appropriate relays or other electrical apparatus.

Another form of wave guide, useful in a combined transmitter-receiver unit of the type shown in Fig. 2, may be as shown in Fig. 8, in which the wave guide 118 branches into individual guides 118A and 118B terminating in paired directional horns HNS and HEW respectively. The said branch guides are gated, and hence a single gate suffices for each pair of horns. An arrangement as shown in Fig. 8, or as shown in Fig. 5 when horns TA and TB and RA and RB are used, is useful in exploring north-south traffic conditions as a group, or east-west traffic conditions as a group, to allocate north-south or east-west right of way as appropriate.

An electronic circuit, employing the familiar multivibrator circuit may advantageously be utilized as the sequence or time switch means for actuating the gates of the respective horns and concomitantly effecting actuation or non-actuation of the relays or other electrical apparatus allocated to the respective gates.

As shown in Fig. 7, a multiple thermionic tube, MT, has a plate P1 interconnected to grid G2; and a plate P2 interconnected to grid G1, through capacitances C1 and C2 respectively, the capacities of which are selected according to the changeover periods desired. Resistances RG1 and RP1 are in series with grid G1 and plate P1 respectively. Similar resistances RP2 and RG2 are in series with plate P2 and G2.

The output from plate P1 is connected to gate B, and to relay A through vacuum tube circuit VTA; the output from plate P2 is connected to gate A, and to relay B through vacuum tube circuit VTB.

The grids of the respective vacuum tubes VTA and VTB are in circuit with the amplified output of the transmitter-receiver unit, in the familiar cathode follower circuit.

As is known to those familiar with the multivibrator circuit, vacuum tube MT, in the circuit shown, operates as a sequence switch, alternately causing flow of current in the respective plate circuits and consequently, in the respective gates A and B.

In the respective relay circuits, current flow in the plate circuit serving gate A makes the plate of tube VTB positive relative to the grid and cathode of tube VTB, and relay B is thereby in circuit with the output from the transmitter-receiver unit during the instant of non-energization of gate B.

The representation in Fig. 2 of the unit 10 mounted at the base of the wave guide 18 does not preclude the installation of said unit at a location remote from the wave guide, with transmission from the unit 10 to antenna 16 by coaxial cable, wave guide, or other suitable means.

From the foregoing, it is apparent that the invention provides for a fully automatic system of systematic examination of traffic conditions on one or several rights of way, and for utilizing the intelligence resulting from such examination for operation of electrical apparatus serving traffic control devices or the like.

Subject matter relating to detection at a particular distance or in a zone corresponding to a particular range of distance per se is disclosed and claimed in my copending application Serial No. 535,937, filed May 17, 1944.

Whereas it is obvious that among the several objects of the invention as specifically aforesaid are achieved, it is apparent that numerous changes in construction and rearrangements of the parts might be resorted to without departing from the spirit of the invention as defined by the claims.

I claim:

1. In a traffic detection system, means for generating an ultra high frequency radio wave; a wave guide including a plurality of directional horns for transmitting said wave in desired directions; gate means in said wave guide for the respective horns to permit or prevent transmission of said wave from said horns as desired; a sequence switch for sequentially operating said gate means to permit periodic transmission from said horns in a prearranged time sequence; means for receiving a reflection wave from an object in the path of said transmitted wave for combination with a wave of the frequency of the transmitted wave; and electric devices individual to each of said gate means and means coordinated with said sequence switch to connect said electrical devices sequentially for each device to be energized by the combined transmitted and reflected waves only during the period when its respective gate means is permitting transmission of said ultra high frequency wave.

2. In a traffic detection system, means for generating an ultra high frequency radio wave; means comprising a wave guide having a plurality of directional horns for transmitting said ultra high frequency wave in desired directions; timer means for controlling the transmission from said directional horns for transmission from selected horns according to a preestablished time schedule; means for receiving a reflection wave from an object in the path of a transmitted wave for combination with a wave of the frequency of the transmitted wave; electric devices individual to said horns for actuation by the electrical energy of the combined transmitted and reflected waves when connected; and means synchronized with said timer means for connecting the electrical device individual to a then transmitting horn to said combined wave energy.

3. Apparatus according to claim 2, in which the timer means includes gaseous tubes for creating across said directional horns, a body of ionized gas capable of reflecting back said waves prior to transmission from said wave guides, and adjustable speed switch means for sequentially impressing across said gaseous tubes, a current capable of ionizing the gaseous content thereof.

4. Apparatus according to claim 2, in which the timer means includes gaseous tubes for creating across said wave guides a body of ionized gas capable of reflecting said waves prior to transmission from said wave guides, and adjustable speed mechanical switch means for sequentially impressing across said tubes, a current capable of ionizing the gaseous content thereof.

5. Apparatus according to claim 2, in which the means for controlling the transmission of said wave from said wave guide comprises a reflecting surface disposed internally of said wave guide and thermionic means for creating and

removing said reflecting surface pursuant to a predetermined time schedule.

6. Apparatus according to claim 2, in which the means for controlling the transmission of said wave from said wave guide comprises a reflecting surface disposed internally of said wave guide and thermionic means including a multivibrator vacuum tube circuit for creating and removing said reflecting surface pursuant to a predetermined time schedule.

7. Apparatus according to claim 2, in which the period of connection of said electrical device to the electrical energy of the combined transmitter and reflected waves is less than the transmission period of the directional horns associated therewith.

8. Apparatus according to claim 2, in which the period of connection of said electrical device to the electrical energy of the combined transmitted and reflected waves commences after the transmission period of the directional horns associated therewith.

9. Apparatus according to claim 2, in which the period of connection of said electrical device to the electrical energy of the combined transmitted and reflected waves terminates prior to the end of the transmission period of the directional horns associated therewith.

10. Means for detecting the presence of vehicles or the like in a plurality of intersecting traffic lanes, comprising means for generating an ultra high frequency radio wave; an antenna for radiating said wave; a waveguide associated with said antenna and disposed at said intersection, and including a directional horn for each traffic lane for directing a radio wave along said lane in a relatively narrow beam; a second wave guide at said intersection and including a second organization of directional horns of substantially the same wave-dispersion pattern as the first named horns and individual to each said traffic lane for receiving a reflection wave representing the reflection of said transmitted wave from a vehicle in the path thereof; a receiver antenna in said second wave guide; an ultra high frequency radio receiver associated with said receiver antenna; means for beating said received reflection wave against the transmitted wave to derive an electrical pulse; output devices individual to each traffic lane and interconnected to said beating means to derive an energizing pulse therefrom; electrical gate means associated with each of said directional horns to permit or prevent alternatively the transmission of said wave from said horns as desired; sequence switch means in circuit with each gate means to actuate each periodically into transmission-permitting status for a brief interval in accordance with a predetermined time sequence; and switch means in circuit with each of said output devices and synchronized with said sequence switch means to connect to the output of said beating means only the output device individual to a then transmitting horn.

11. Means for detecting the presence of vehicles or the like in a plurality of traffic lanes, including means for generating an ultra high frequency radio wave; an antenna for radiating said wave; a wave guide including a plurality of directional horns each individual to a selected traffic lane to transmit said radio wave in a narrow beam along its selected traffic lane; means for receiving a reflection wave from an object in the path of a transmitted wave and for beating said received wave against the transmitted wave

to derive a beat frequency wave; output means from said receiving means; electrical gate means associated with each of said directional horns to permit or prevent alternatively the transmission of said wave from said horns as desired; sequence switch means in circuit with each gate means to actuate the same periodically from transmission permitting to preventing and return in accordance with a pre-determined time sequence providing individual transmitting periods for the respective horns; electric devices individual to each said directional horn and in circuit with the output of said reflection wave receiving means to be energized thereby, and means synchronized with said sequence switch means to connect only the electrical device individual to a then transmitting horn to the output of said receiving means.

12. Means for periodically exploring a plurality of traffic lanes to detect the presence of vehicles or the like therein; comprising means for generating an ultra high frequency radio wave; antenna means for radiating said wave; a wave guide including horns equal in number to the number of traffic lanes to be explored and individually directing said wave in a relatively narrow beam along one of said lanes; means for receiving a reflection wave from an object in the path of a transmitted wave and for beating said received wave against the transmitted wave to derive a beat frequency wave; an electrical circuit energized by the output of said receiving means; gate means associated with said transmitting wave guides, to permit or prevent alternatively the transmission of said wave; switch means in circuit with said gate means to actuate the same individually to so permit transmission for relatively brief time periods, according to a predetermined sequence schedule; electrical devices individual to each said transmitting wave guide and in circuit with the output circuit of said receiving means to be energized thereby; and means synchronized with said switch means to connect an output means of a wave guide into said receiver output circuit only during the intervals when the gate of said wave guide is in wave-transmitting status.

13. Apparatus for detecting traffic in two distinct traffic paths entering a traffic intersection common to such paths comprising means for directing a beam of ultra-high frequency electromagnetic waves from the vicinity of the intersection successively along each of the paths alternately, means for receiving waves reflected from traffic as a result of encounter of the beam therewith, a plurality of output devices each associated with a different one of said paths for utilizing the received waves, and means for operatively associating said output devices with said receiving means for response to said received waves successively in coordination with the transmitting and receiving of the waves alternately in the respective paths to detect and distinguish traffic in the respective paths.

14. Apparatus for detecting traffic in a plurality of distinct traffic paths entering a traffic intersection common to such paths including means for generating ultra-high frequency electromagnetic waves, means for directing such waves along each of said paths, cyclic time controlled means for transmitting and interrupting transmission of such generated waves via said directing means in a time cycle including separate transmission periods for the respective paths, means for receiving waves reflected from traffic in such lane, a plurality of translating

devices for the respective paths for utilizing such received waves to detect traffic, and means for operatively associating said translating devices with said received waves for response thereto successively in coordination with the transmission periods in the respective paths to distinguish traffic in the respective paths.

15. In a traffic detection system employing ultra-high frequency radio waves, wave directing means individual to each of two distinct directions, means for generating such waves and means for receiving such waves reflected from traffic in such directions, said generating and receiving means being common to said wave directing means for the two directions, means for alternately causing and interrupting transmission of such waves via the respective wave directing means in a cyclic sequence including one period of transmission in one only of such two directions and a separate period of transmission in the other only of such directions, a plurality of output circuits including one for each of such directions and means connecting the output circuits to said receiving means in sequence in coordination with transmission in the corresponding direction to distinguish traffic in the respective directions.

16. In a traffic control system, means for periodically detecting vehicles along a plurality of traffic lanes, comprising an ultra-high frequency wave generator and ultra-high frequency wave receiver; a wave guide system for said generator and said receiver and having means for directionally transmitting said ultra-high frequency waves along said traffic lanes respectively and for receiving a wave reflected from vehicles in said lane; means for controlling transmission of said wave along said traffic lanes and the reception of a reflected wave therefrom in substantially synchronized periods according to a pre-determined time sequence for distinguishing traffic in the respective lanes; said wave guide system including directional horns so disposed with respect to the traffic lanes as to provide within each said traffic lane, a substantially clearly defined detection zone in which a vehicle is exposed to said ultra-high-frequency waves.

17. In a traffic control system, means for pe-

riodically detecting vehicles along a plurality of traffic lanes, comprising an ultra-high frequency wave generator and ultra-high frequency wave receiver; a wave guide system for said generator and said receiver and having means for directionally transmitting said ultra-high frequency waves along said traffic lanes respectively and for receiving a wave reflected from vehicles in said lane; means for controlling transmission of said wave along said traffic lanes and the reception of a reflected wave therefrom in substantially synchronized periods according to a pre-determined time sequence for distinguishing traffic in the respective lanes; said wave guide system including directional horns disposed at an elevated level above said traffic lanes.

18. In a traffic detection system as in claim 15, said output circuits including relays individual to said circuits for operation in response to such received waves when the respective output circuits are connected to said receiving means.
